IRON BENDING MACHINE

Albert Hossfeld, Winona, Minn.

Application May 3, 1944, Serial No. 533,963

1 Claim. (Cl. 153—45)

1

My present invention relates to improvements in iron bending machines of the type disclosed and broadly claimed in my United States Letters Patent No. 1,832,210, issued November 17, 1931, and entitled "Die for bending angle bars."

The objects of this invention are: first, to provide a simple and highly efficient machine for bending a flat metal bar in the plane thereof; second, for holding the bar from buckling while bending the same; and third, to permit free end-wise feeding movement of the bar in the machine when the bending pressure is removed therefrom.

To the above end, generally stated, the invention consists of the novel devices and combination of devices hereinafter disclosed and claimed.

In the accompanying drawing, which illustrates the invention, like characters indicate like parts throughout the several views.

Referring to the drawing:

Fig. 1 is a fragmentary plan view of the improved iron bending machine, some parts being shown in section;

Figs. 2 and 3 are views in vertical section taken on the line 2—2 and the irregular line 3—3 of Fig. 1; and

Fig. 4 is a bottom plan view of the radius block.

The improved bending machine includes a stationary main frame 5 and a swinging bending frame 6 attached to said main frame by a pivot pin 7 for horizontal swinging movement. Said main frame 5 is rigidly secured to a bench or other support, not shown, by a plurality of nut-equipped bolts 8.

Each frame 5 and 6 includes a pair of vertically spaced flat bars 9 and 10, respectively. The inner end portions of the bars 10 of the swinging frame 6 are interposed between the adjacent ends of the bars 9 of the main frame 5 with a close working fit. The pivot pin 7 extends through aligned holes in the bars 9 and 10. A hand lever, not shown, is attached to the outer ends of the bars 10 for use in swinging the frame 6.

A master die 11 is interposed between the bars 9 and 10 and pivotally secured to the pairs of bars 9 and 10 by the pivot pin 7. Integral with the master die 11 is a pair of forwardly projecting wedge-acting members 12. Also integral with the master die 11 is a forwardly projecting work-supporting table 13, located below the wedge-acting members 12. The outer faces of the master die 11 and the outer edge of the work-supporting table 13 are on arcs of concentric circles.

Co-operating with the master die 11 is a radius

block 14, the front and back thereof being on arcs of circles that are concentric with the face of the master die 11. This radius block 14 is positioned over the work-supporting table 13 and has in its back a pair of notches 15 into which the wedge-acting members 12 project. The bottoms of the notches 15 are upwardly and outwardly inclined and slidably engage the oblique under surfaces 16 of the wedge-acting members 12. On the under side of the radius block 14 is a curved rib-like stop member 17 that is integral with said block and affords a base of resistance for a flat iron bar x resting flatwise on the work-supporting table 13 and being bent in the plane thereof. Or in other words, the stop member 17 takes the thrust of the bending pressure applied to the bar x by the bending block 19. This stop member 17 is on a segment of a circle that is concentric with the front and back surfaces of the radius block 14.

A stop block 18 on the main frame 5 is provided for holding the bar x against the stop member 17 and a bending block 19 is mounted on the swinging frame 6. These two blocks 18 and 19 are identical, the one with the other. The stop block 18 extends between the bars 9 and is secured thereto by a pivot pin 20. This pivot pin 20 extends through one pair of a plurality of longitudinally spaced holes 21 in the bars 9.

The bending block 19 is interposed between the bars 10 of the swinging frame 6 and secured thereto by a pivot pin 22. The pivot pin extends through one pair of longitudinally spaced holes 23 in said bars.

As shown, the left-hand end portion of the bar x has been bent around the stop member 17 on the arc of a circle having the same radius as the engaged edge of said member. The other end portion of the bar x is straight. This bar x rests on the work-supporting table 13 and, in turn, the radius block 14 rests on the bar x. It is important to note that the radius block 14 is out of contact with the master die 11 and its stop member 17 is out of contact with the work-supporting table 13.

It will be noted that the bar x, at its outer edge, engages the stop block 18 and is held thereby against the stop member 17. The bending block 19 is in engagement with the outer edge of the straight portion of the bar x and considerably in advance of the curve in said bar.

Obviously, by pulling the swinging frame 6 toward the bar x, said bar will be bent in the plane thereof by the contacting bending block 19 around the curved stop member 17. During

bending of the bar x , the pressure thereof on the stop member 17 will force radius block 14 toward the master die 11 . As the radius block 14 moves toward the master die 11 , the engagement of said radius block 14 with the wedge-acting members 12 will force the radius block 14 downwardly onto the underlying bar x . It will thus be seen that the bar x will be tightly clamped flatwise between work-supporting table 13 and the radius block 14 and thereby prevent buckling of the bar x during bending thereof.

The above described iron bending machine will, in actual usage, be provided with a plurality of radius blocks having stop members 17 of different radii. The master die 11 will take care of quite a range of sizes of radius blocks 14 from small radii up to quite large radii.

The drawing illustrates a commercial form of the invention, but it will be understood that the same is capable of certain modifications as to details of construction arrangement and combination of parts within the scope of the invention herein disclosed.

What I claim is:

In a device of the class described, a die having a work table for supporting thereon a flat piece of metal to be bent on the arc of a circle, a radius block overlying the table to be supported on the bar and having on its under side a stop shoulder to be engaged by the bar at its inner edge, and holding the bar with its outer edge portion outwardly of the die and the radius block, the faces of the die and radius block and the stop shoulder being on the arcs of circles, the width of the stop shoulder being less than the thickness of the bar, whereby said stop shoulder is out of engagement with the table, a stop to be engaged by the bar at its outer edge for holding said bar with its inner edge against the stop shoulder, a bending device operative on the outer edge of the bar in advance of the stop for bending the bar on the stop shoulder, and means actuated by pressure generated by bending the bar to force the radius block onto the bar and clamp the same onto the table.

ALBERT HOSSFELD.
